UNITED STATES PATENT OFFICE.

ROBERT FLEMING ARNOTT, OF UPPER MONTCLAIR, NEW JERSEY, ASSIGNOR TO I. L. MYERS, OF NEW YORK, N. Y.

MANUFACTURE OF PAPER CARTONS.

1,221,649.

Specification of Letters Patent.

Patented Apr. 3, 1917.

Application filed March 22, 1913. Serial No. 756,141.

To all whom it may concern:

Be it known that I, ROBERT F. ARNOTT, a subject of the King of Great Britain, residing at Upper Montclair, in the county of 5 Essex and State of New Jersey, have invented a new and useful Improvement in the Manufacture of Paper Cartons, of which the following is a full, clear and exact description, reference being had to the accompanying drawings, forming part of this specification, in which:

Figure 1 is a sectional side elevation of one form of machine embodying my invention; and

Fig. 2 is a portion thereof on a larger scale.

Fig. 3 is a detail sectional view showing a portion of a two-ply paper band.

My invention relates to the manufacture 20 of paper cartons by winding paper about a mandrel and cementing it in wound form.

The object of the invention is to make the walls of the package stiffer and denser, and reduce their tendency to soften in contact with liquid.

In the co-pending application of C. C. Stutz and myself, No. 678,110, filed Feb. 16, 1912, we describe a machine for this purpose. In such machine, the paper whether 30 single or multiple ply is fed forward and directed around the mandrel, the feeding forward being positive except for the last end passing on to the mandrel.

I have found that the character of the 35 package is improved if a plurality of the last wraps are pulled on to the mandrel by the winding action thereof, as distinguished from feeding the paper forwardly on to it. This pulling action for the last wraps draws 40 the plies together more tightly and firmly so that the walls are stiffer, the cement is more completely spread and the tendency to soften under contact with liquid is reduced.

In carrying out my invention, I preferably use a band of paper consisting of two or more plies or layers instead of a single 50 ply, although the invention may be used with a single ply; and by the words "band" or "strip" in my claims, I intend to cover either the single or multiple form of strip.

In the drawings, in which I show one form of apparatus for carrying out my in-

vention, 2 represents the roll of paper supply, and 3 the strip or band drawn therefrom. This strip passes under an idle roller 4 and thence between printing rolls 5 and 6 from the lower of which it passes downwardly, as shown by the arrow, around the idle roller 7, and thence upward in the 60 direction of the arrow and over the idle roller 8 at the entrance to the heated chamber 9. Within this heated chamber or box, it passes under the idle rollers 10, which are immersed in hot liquid paraffin contained in the tank 11. From this tank it passes between the feed rolls 12—12 and thence under the cutting knife 13 to the mandrel 14. As the strip passes from the feed rolls 12 to the mandrel 14, it rests upon 70 suitable supports 15 and is held against the mandrel by pressure roller 16.

The cutting knife 13 is hung between the feed rolls 12 and the mandrel, being secured to a pivoted link 18 mounted on lever 20 fulcrumed at 21 on a rocking support 22 and guided by pin 23 moving in slot guide 24. The roller at the rear end of this lever is actuated by a cam 25 on shaft 26, driven through belt or chain 27.

In the operation of the machine, the continuous strip of paper, preferably of the multiple ply or layer form, is fed through the printing rolls to print any desired matter thereon and thence passes into the heating chamber. Here it is supplied with or soaked in hot liquid paraffin, either by passing it through the bath, as shown, or spraying the paraffin thereon, or in any other desirable manner. It is then fed forward 85 to the mandrel 14 and positively fed on to the mandrel. The mandrel, feed rolls and printing rolls are positively driven through a certain number of turns of paper as it is wound on the mandrel. The feeding action 90 of the feed rolls and printing rolls is then stopped while the mandrel continues to be driven. In this manner, the mandrel will pull upon itself the rest of the wraps by drawing the paper band through the rolls 100 and between the idle rollers, etc. When the mandrel has thus wound up the desired number of turns, the knife is brought into action and the paper cut transversely. The portion of the band back of the knife remains stationary while the mandrel winds 105

up the remaining end, thus forming a complete cylinder which is removed by any desirable stripping action. After the removal of the wound cylinder from the mandrel, 5 the feed rolls and printing rolls automatically start again and the next length of paper is fed forward to the mandrel and the operation repeated.

In this improved system, therefore, the 10 paper band is first fed forward upon the revolving mandrel for a certain number of turns or wraps and the feeding is then stopped and the mandrel itself actuated to pull forward and wind upon itself the remaining turns or wraps, the paper being automatically cut at the desired time. Thus, 15 in case it is desired to feed four wraps or turns upon the mandrel and pull two additional turns thereof to give a cylinder of six 20 wraps; the roll 5 may be made with its diameter four times the diameter of the mandrel, its intermittent driving gearing being arranged to give it one complete revolution and then stop, while the mandrel continues 25 to rotate. When the printing rolls stop, the point where the paper band will be later on cut with the knife will be in about the position marked K on the roll 5. The band or strip will then be pulled forward by the 30 mandrel until the point K arrives at the cutting point where it is cut. The length of paper from the point K to the point L should be equal to the length to be pulled forward, or to this length plus any number 35 of lengths required to form a complete cylinder. A surplus may also be provided so that the outer end may overlap the inner end by any desired amount.

In carrying out this system, I find it of 40 advantage to slightly depress the lower feed roller 12 at about the time it ceases turning. In the form shown to carry out this movement I support the bearings of this roller on springs 28 from which bearing rods 29 extend down to the cross-bar 30. This cross-bar is acted upon by cam lever 31 having a roller 32 actuated by the cam 33. This cam slightly lifts the roller end of the lever at the proper time and depresses the roller 12 50 as it stops turning.

I also prefer to hold the band stationary while the knife is cutting it. For this purpose I show a slide 34 having a roller 35 actuated by cam 36. The other end of 55 this slide has a pivotal connection with the rock lever 37 fulcrumed at 38 and having a braking surface at 39 which is adapted to press upon the band. The cam 36 is so timed that it will depress the brake against 60 the band and while the knife is cutting the band.

Any suitable gearing may be employed for effecting the intermittent driving of the feeding and printing rollers 5, 6 and 12, while 65 the rolls 5 and 6 may be geared to each other

so as to rotate in unison. In the drawings I have shown the machine as having a main driving shaft 40 carrying a sprocket wheel 41 which drives a chain belt 42 through a chain wheel 43 on the shaft 44. This shaft 70 44 carries a large spur gear wheel 45 which meshes with the pinion 46 on the shaft of the arbor. The roller 5 is driven from the shaft 44 through a chain belt 47 on a chain wheel 48 carried by the shaft 49. On the shaft 49 75 is a mutilated gear wheel 50 which is arranged to mesh with a pinion 51 on the shaft of the printing roller 5. This shaft also carries a chain wheel 52 driving a belt 53 which in turn drives the shaft of the upper roller 12. By means of this gearing the mandrel 14 will be continuously driven while the rollers 5, 6 and 12 will be driven only when the toothed portion of the mutilated gear 50 is in engagement with the pinion 51. 80

Where a multiple strip or band is used, the multiple layers may be upon the same supply roll, or a plurality of supply rolls may be used, each containing one layer or 85

90 The advantages of my invention result from the pulling forward of the last wrap or wraps in order to tighten and densify the walls and give a stronger, stiffer package. Air between the layers is more thoroughly 95 forced out, the cementing material is more thoroughly spread among the layers, and the tendency of the package to soften under contained liquid is greatly reduced.

The number of wraps fed forward and the 100 number of wraps pulled on the mandrel may be varied as desired, and many different forms of apparatus may be used for carrying out this result, since I consider myself the first in winding cartons to feed the paper 105 forward for a part of the wraps and then pull it on the mandrel for the succeeding wraps.

I claim:

1. The method of forming stiff-walled 110 paper cans, consisting in winding directly on a mandrel a plurality of wraps of paper, and finally stiffening the wall and consolidating the previously wound layers of paper by winding one or more final wraps under 115 a tension considerably greater than the first wraps, substantially as described.

2. The method of forming stiff-walled 120 waterproof paper cans, consisting in applying a waterproofing material to a strip of paper, winding a plurality of wraps of such waterproof strips directly around a mandrel, and finally stiffening the wall, consolidating the previously wound layers and more completely spreading the waterproofing material by winding one or more final wraps under a tension considerably greater than the first wraps, substantially as described. 125

3. The method of forming stiff-walled 130

waterproofed paper cans, consisting in saturating a strip of paper with paraffin or the like, winding a plurality of wraps of such saturated strips directly around a mandrel, 5 and finally stiffening the wall, consolidating the previously wound layers and more completely spreading the paraffin by winding one or more final wraps forming the outer

plies of the can under a considerable tension, substantially as described.

In testimony whereof, I have hereunto set my hand.

ROBERT FLEMING ARNOTT.
